UNITED STATES PATENT OFFICE.

JOHN N. HELTZEL, OF WARREN, OHIO.

CONCRETE FORM.

Application filed December 8, 1925, Serial No. 74,106. Renewed July 13, 1928.

This invention relates to concrete forms and more particularly to road forms using rails for defining the edges of a concrete road, side-walk or the like, this invention being an improvement upon the concrete form disclosed in an application filed by me January 12, 1924, Serial No. 685,811.

A particular object of the present invention is to improve the means for joining and securing the rail ends together, using a stake for each rail end, and a simple and convenient means for simultaneously clamping the two stakes of the joint.

A further object is to house and protect the wedging or locking members and their associated parts so that the working parts of the joint will be protected from deposits of cement and thus be free to operate under all conditions of service.

20 A still further object of the invention is to so construct the joint elements that they will span the abutting ends of adjacent form sections so as to reinforce the structure and prevent sagging at the joints thereof as well 25 as preventing accidental parting movement of the form sections at said joints.

Other objects will appear in the course of the following description, and the invention resides in certain novel features which are 30 illustrated in the accompanying drawings and will be particularly pointed out in the appended claims.

In the drawings:

Figure 1 is a perspective view showing one 35 embodiment of the invention arranged for use;

Fig. 2 is an enlarged sectional elevation of the joint shown in Fig. 1;

Fig. 3 is a transverse vertical section on 40 the line 3—3 of Fig. 2;

Fig. 4 is a detail perspective view of the locking or wedging member employed to clamp the stakes;

Fig. 5 is a perspective view partly broken 45 away showing an embodiment of the invention differing in some respects from that shown in Figs. 1 to 4;

Fig. 6 is a vertical section on the line 6—6 50 of Fig. 5.

Forms such as are used in the construction of concrete roads, side-walks and the like comprise rail or side members having upright webs 1, outturned base flanges 2 at their lower edges and upstanding lips or bearing flanges 3 at the outer edges of the said base flanges. Extending outwardly

from the upper edges of the upright webs 1 are tread flanges 4, from the outer edges of which depend the lips or bearing flanges 5. These rails are laid end to end and the road 60 or concrete structure is built up between opposite rails which serve to define the edges of the road, while the flanges 4 define the surface of the road at the opposite edges.

At each joint, or each place where the opposed ends of aligned rails meet or abut, I provide anchoring means comprising a joint member which bridges the ends of the rails and is provided with means for receiving two stakes and through which is mounted a single member for simultaneously clamping both stakes. The joint member comprises an inclined web 6, shown most clearly in Fig. 3, having its upper edge portion formed into an inverted U-shaped tread section comprising a central web 7 and side webs or flanges 8 and 9 adapted to fit snugly between the web 1 and the lip 5 of the rails and against the tread flange 4 of the same, the lower end edge of the inclined web 6 fitting in the angle defined by the base flange 2 and the upstanding lip or outer flange 3, as clearly shown in Fig. 3. The joint member includes a pocket element which consists of an upper horizontal web 10 extending longitudinally 80 of the web 6 of the joint member, a lower horizontal web 11 which also extends longitudinally of the web 6, and an outer vertical web 12 integral with and rigidly uniting the outer edges of the webs 10 and 11. The inner edge of the web 11 is welded or otherwise intimately united with the web 6 at such a point above the lower edge thereof that the said web 11 will extend across the lip 3, while the upper web 10 has its inner edge portion 90 disposed obliquely, as shown at 13, whereby it may rest flat against the web 6 and be united therewith, preferably by rivets, as indicated at 14. Through the webs 10 and 11, immediately adjacent the vertical web 12 and 100 near the ends of the said webs 10 and 11, slots or openings 15 are formed therethrough to receive the stakes 16, as shown. The stakes are driven into the ground so as to engage or bear against the upstanding lip or bearing flange 3 of the respective forms, it being noted that the slots or openings 15 will be disposed at opposite sides of the vertical plane in which the meeting ends of the rails or forms abut so that, when the forms are in 110 place, there will be one stake at each end of each rail. The stakes are tapered at their

lower ends so that as they are driven into the ground they will bind against the flange or lip 3 and, therefore, exert pressure upon the same and upon the web 6 which will tend 5 to force the joint member into binding engagement with the rails at their abutting ends and assist in preventing accidental separation thereof. It will be readily noted that the pocket element defined by the webs 10, 10, 11 and 12 is so arranged upon the web 6 that a space or open-ended slot 17 is formed 15 through the joint member and within the said space or slot is mounted a locking or wedging member 18. This wedging member, in the illustrated embodiments of the invention, consists of an angle bar having a horizontal web 19 and a vertically disposed web 20 extending longitudinally of the joint member and of greater length than 20 the joint member so that its ends may protrude from the ends of the slot or space 17 to be engaged by a setting tool, such as a hammer. Through the upper horizontal web 19 of the locking or wedging member 25 are formed parallel obliquely disposed slots 21 through which are engaged the stems or shanks 22 of rivets having their upper heads 23 bearing upon the upper surface of the web 10 and their lower heads 24 spaced 30 from the said web 10 a distance slightly greater than the thickness of the web 19 whereby said web 19 may slide easily between the web 10 and the head 24 but will be positively supported by the said head 24. 35 It will be noted that the slots 21 and the rivets which support the locking or wedging member are arranged in alignment with the respective stakes transversely of the joint member so that the pressure exerted 40 by and resulting from the engagement of the rivets and the outer walls of the slots 21 will be distributed to the respective stakes and both stakes will be firmly secured.

The stakes are preferably provided with 45 enlargements or projections 25 near their upper ends which, by contact with the upper surface of the web 10 of the joint member, will limit the downward movement of the stakes and thereby prevent them being buried 50 to such an extent that their upper ends would be disposed within the joint members and, consequently, prove inefficient to hold the device against endwise movement. Moreover, these enlargements or projections furnish 55 convenient means for engagement with a pry when it is desired to withdraw the stakes from the ground and release the forms.

In assembling the parts, the joint member 60 is slid endwise into engagement with the end of one rail or form and the next rail or form is then brought endwise into engagement with the joint member, the joint member bridging the ends of the rails so as to positively support both rail ends and prevent sagging at 65 the joint. The stakes are then driven through

the slots or openings 15 in the pocket section of the joint member, the wedging or locking key at this time being so disposed that the ends of the slots 21 nearer the outer vertical web of the said member will be engaged with 70 the supporting rivets, or at least the vertical web 20 of the locking member will be out of contact with the stakes. After the stakes have been driven through the pocket element, the locking or wedging member is moved endwise or longitudinally of the joint member so that its vertical web 20 will engage and bear 75 against the faces of the stakes opposed thereto. The slots 21 are not only parallel but are of equal extent and are so arranged that the corresponding ends of the two slots are at 80 equal distances from the side edges of the wedging or locking member. Consequently, the said member will always be supported 85 parallel with the stakes or the openings through which the stakes are inserted so that, when the endwise movement is imparted to the wedging member, it will simultaneously bear against the two stakes and clamp them to the vertical web 21 of the pocket element. 90

It will be readily seen from the foregoing description, taken in connection with the accompanying drawings, that I have provided an exceedingly simple mechanism whereby the meeting ends of the form rails will be firmly supported and may be quickly anchored in place. If, before the concrete material has been laid, it is desired to temporarily remove one section of a rail or form to permit wagons carrying the concrete or other road material to pass onto the roadbed, the wedging member may be loosened and it will then be a simple matter to withdraw the desired rail section. The two stakes may be raised and the joint member then slid endwise so as to be entirely within the rail which is to remain in place, whereupon the rail to be removed may be lifted vertically without interference from any of the securing elements. It will also be noted that the joint member is of such form that it completely houses the wedging or locking member and also covers such slight space as there may be between the abutting ends of the rails so that the working parts will be protected from deposit of portions of the cement which might flow over the tread flanges of the rails, the locking elements being, consequently, always in operative condition. 110

In Figs. 5 and 6, I have illustrated an embodiment of the invention slightly different from the previously described embodiment. In this form of the invention, the base member 30 of the rail form is made slightly wider than the base member 2 in the first described form so that the upstanding flange or lip 31 will be in a vertical plane outwardly beyond the vertical web 12 of the pocket element. The web 32 of the joint member is somewhat longer than the corresponding web 6 illus- 120 125 130

trated in Figs. 1, 2 and 3 so that its lower edge may engage in the angle defined by the base flange 30 and the lip 31, as will be understood upon reference to Fig. 6. As a result of this increase in size of the inclined web, the lower edge portion thereof will be disposed below the web 11 and the web 12 of the pocket element, and slots or openings 33 are formed through this extended portion to receive the lower end parts of the stakes 34, while similar slots or openings 35 are formed through the base flange 30, the openings or slots 33 and 35 being obviously aligned vertically with the openings 15 in the pocket member. The same locking member 18 is employed and the action is in all respects the same as that in the first described form, with the exception that the stakes pass through the base flange of the rail forms and thereby positively lock the forms or rails to the joint member instead of merely bearing against the outer face of the upstanding lip or flange as in the first described arrangement. This construction also positively prevents accidental parting or separation of the form sections at the abutting ends thereof.

Having thus described the invention, I claim:

1. A concrete form having means for receiving two stakes, and a single element arranged to simultaneously clamp both stakes.

2. A concrete form comprising rails, two stakes, means for connecting said stakes and rails, and a single element carried by said means arranged to simultaneously clamp both stakes.

3. A concrete form comprising rails, two stakes, means for connecting said stakes and rails and having a slot, and a wedge slidably in said slot to simultaneously clamp both stakes.

4. In a concrete form, a member having means to receive two stakes, and means carried by said member operable with a single operation to simultaneously clamp both stakes.

5. In a concrete form, a member having means for receiving two stakes, and a wedge carried by said member arranged to simultaneously clamp both stakes.

6. In a concrete form, a member having means for receiving two stakes, and a wedge to engage both of said stakes, said member having means for the contact of the wedge arranged to distribute the pressure to both stakes.

7. A concrete form comprising rails, pocket elements engaged with the rails, stakes passing through the pocket elements and engaging the bases of the rails, and a single element carried by the pocket element to simultaneously clamp both stakes.

8. A concrete form comprising alined rails,

a joint member slidable between the tread and the base of the rails and bridging the abutting ends of the rails, stakes driven through the joint member and engaging the bases of the rails whereby to prevent parting movement of the abutting ends of the rails, and means to simultaneously clamp both stakes.

9. A concrete form comprising rails, a pocket member fitted to the rails and having stake-receiving means for two stakes, and a single element movable longitudinally in the pocket member to simultaneously clamp the two stakes.

10. A concrete form comprising alined rails, a joint member engaged in the meeting ends of the rails and bridging the joint between the same, said joint member being provided with stake-receiving means for two stakes, stakes engaged in said stake-receiving means and engaging the bases of the rails, and means mounted on the joint member for simultaneously clamping both stakes.

11. A concrete form comprising rails, a joint member engaged with the ends of the rails and bridging the joint between the same, a pocket element upon the joint member having a slot extending therethrough longitudinally of the joint member, stakes engaged through the pocket element adjacent the ends thereof and engaging the base portions of the rails, and a wedge slidable in the slot of said pocket element to simultaneously clamp both stakes.

12. A concrete form forming alined rails, a joint member engaged with the rails to bridge the joint between the same, a pocket element on said joint member having means for receiving two stakes and having a slot extending longitudinally therethrough, stakes engaged through the stake-receiving means and engaging the base portions of the rails, fixed supports in the pocket element, and a clamping member having spaced parallel obliquely disposed slots engaged with said supports whereby longitudinal movement of said locking member will simultaneously clamp both stakes.

13. A concrete form comprising rails having base flanges and provided with openings through said flanges at their ends and adjacent their outer edge portions, a joint member snugly engaging the ends of the rails, a pocket element on the joint member, there being openings formed through the pocket element and the joint member alined vertically with the openings in the base flanges of the rails, stakes engaged through the several vertically alined openings, and a wedge mounted in the pocket element to simultaneously clamp the stakes.

In testimony whereof I affix my signature.
JOHN N. HELTZEL.
